UNITED STATES PATENT OFFICE.

PIERRE ROOS, OF NEW YORK, N. Y.

HAIR-CURLING APPARATUS.

1,206,917.

Specification of Letters Patent.

Patented Dec. 5, 1916.

Application filed September 18, 1913. Serial No. 790,448.

To all whom it may concern:

Be it known that I, PIERRE Roos, residing at 18 East Forty-sixth street, in the city of New York, county of New York, and State of New York, have invented certain new and useful Improvements in Hair-Curling Apparatus, of which the following is a specification.

This invention relates to a hair drying and curling apparatus, and while it is particularly adapted for use in hair dressing parlors and like places, it is as well adapted for home use, if desired.

A particular object of the invention is to provide a convenient mechanism, whereby the strands of hair from the various parts of the head of the user may be simultaneously operated upon without discomfort to the user.

20 A further and more particular object is to provide a mechanism comprising a required number of heating and drying devices supported in such manner as to be adjustable in all directions with respect to each other, 25 these drying devices being constructed to receive portions of the strands of the user's hair and to retain the strands in a natural position without pulling the hair or otherwise discomforting the user, the heating devices 30 being conveniently connected to a source of electricity or other means for warming them.

35 A further object is to provide a simple and efficient curling device about which the strands of hair may be engaged and held in a desired twisted or curled condition while within the heating devices, the curling devices also serving to retain the hair to facilitate its introduction into the heating 40 devices.

45 Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

50 In the accompanying drawings which are to be taken as a part of this specification, and in which I have shown a merely preferred form of embodiment of the invention:

55 Figure 1 is a perspective view of a mechanism constructed in accordance with the

provisions of this invention, and illustrating the manner of use thereof; Fig. 2 is a side elevational view, partly in section, of one of the heating devices, detached; and 60 Fig. 3 is a perspective view of one of the curling devices.

With the above objects in view, the invention comprises parts, an illustration of one form of which is shown in the drawings, 65 and this illustration may be described in detail as follows:—The numeral 1 indicates a lighting fixture, such as is in common use and which comprises preferably a cylindrical pipe or standard of uniform diameter. 70 The upper end of this pipe is connected to the ceiling or other support as at 2. At the lower end is provided a device 3 formed with a number of outlets 4, all of which is common to an ordinary lighting fixture. 75 Within the outlets 4, screw plugs or other terminal means may be detachably engaged to transmit electric current from the outlets 4 along flexible cords 5 to the heating devices 6. The heating devices may be detachably connected to the cord 5, if desired, 80 through the medium of socket circuit breaking devices 7. The heating devices 6 are each independently supported at the lower end of a cable or chain 8 which extends 85 upwardly about a pulley 9, and has its opposite end counterweighted as by a weight 10. The weights are of substantially the same weight as the heating members, and 90 serve to maintain the heating members at any selected elevations. To support the pulleys 9 for the several heating members, I provide a bracket or support 11, which comprises a sleeve 12, mounted upon the pipe 95 of the lighting fixture near the upper end thereof, and capable of being adjusted along the pipe, and held in any adjusted relation by set screws 13. Extending in radial directions from the sleeve 12 are a plurality of rods 14, one for each heating member. 100 These rods are preferably of a uniform cross-section, and the pulleys 9 are provided to slide longitudinally thereon so as to be adjusted nearer to or farther from the center of the structure, as may be desired. Set 105 screws 15 may be provided for retaining the pulleys in any adjusted position.

110 In order to give a greater and more convenient range of adjustability in positioning the heating devices 6 about the head of a user, I have provided a second bracket 16 near the lower end of the pipe of the light-

ing fixture. This bracket 16 is provided with a plurality of arms, preferably one for each of the heating devices, the same as the bracket 11 just described. The arms of the bracket 16, however, are somewhat longer than the arms of the bracket 11, and at their ends are forked as at 17, to provide seats within which a cable 8 may rest, when it is desired to hold the heating device of that cable in a position greatly removed from the center of the structure. Along the length of each of the arms of the bracket 16, are provided forked members 18. These are adapted to be engaged by the cables 8, when it is desired to hold a heater at a position relatively nearer the center of the structure. The arms of the bracket 16 are pivotally mounted at their inner ends, as at 19, between spaced flanges of a sleeve 20, mounted upon the pipe of the lighting fixture adjustable vertically thereof by set screws 21.

From the above description, it will be apparent that a person desiring to use the apparatus may stand or sit beneath the same, and the heating members 6 of the device may be adjusted to any desired position, relative to her head, either vertically or horizontally, the vertical adjustment being accomplished with the use of the counter-weighted cables, and the horizontal adjustment being accomplished by swinging the arms of the bracket 16 about their pivots and adjusting the cables upon the forked members or seats 17-18. The intermediate portions of the wires 5 may obviously be caught up and supported upon the arms of the bracket 16 or upon the forked members 17-18, if desired, as shown in Fig. 1.

An apparatus constructed as above may be readily installed in hair-dressing parlors and the like. After the operator has adjusted each of the several heating devices into the most appropriate positions to suit the individual customer, he may then adjust all of the heating devices collectively as an entity, that is, without changing their positions relatively to each other, and even without changing their collective position relatively to the customer's head, in case the customer desires to change from a sitting position to a standing position, or vice-versa. The several heating devices may be thus collectively adjusted as an entity for any desired purpose after having been adjusted with relation to each other, by merely sliding the bracket or support 11 vertically of the standard 1.

The lower bracket 16 may be adjusted vertically of the standard whenever occasion requires. In some cases it is desirable that this bracket be arranged quite close to the customer's head so as to hold the heating devices against undue lateral movement. In such cases it becomes necessary to change the elevation of the bracket 16 according to

whether the customer is in a standing or a sitting position, etc. The adjustability of the two brackets thus coöperate to produce a highly desirable and valuable feature of this invention.

It is, of course, not desired to limit the scope of this invention to the use of an ordinary electric light fixture. Obviously any other appropriate structure may be employed or an especially designed one might be provided. Although it is desirable that the standard be supported from above, nevertheless, it might clearly be otherwise supported, either from its lower end or even from its intermediate portion. A support upon the ceiling of a room is not essential, but is merely illustrated herein as an example.

It may be noted further that the provision whereby the pulleys or rollers 9 are adjustably supported upon the arms of the bracket 11 may be made use of for adjusting the heaters laterally with respect to each other in lieu of the means provided in the bracket 16, if desired. These two features for effecting lateral adjustment serve as auxiliaries to each other.

As an example of a type of heating device adaptable to use in connection with this invention, I have illustrated the structure shown in Fig. 2. This heater comprises a tubular member having double walls, between which walls is arranged an electrical heating element for heating the hollow of the tube.

The curling devices illustrated, comprise a pair of tubular members 22, pivotally connected together by one of their ends as at 23. Each of these members is formed with a plurality of apertures through its walls at spaced intervals along their length. The strands of hair may be wound or curled about the tubes in any desired manner, and the free ends of the tubes brought together to hold the hair in that position while being introduced into, and while contained within, the heating device. If desired, the hair may be slightly moistened or otherwise treated prior to being inserted within the heater. The apertures through the walls of the tubular members 22 of the curlers permit the entrance of heat into the hollows of the tubular members and facilitate the drying process.

It has been found that hair wound or curled upon curlers of this general description, and placed within heating devices, as illustrated, and dried while curled about the curlers, will maintain a curly or wavy appearance for a week or more, after the curlers are removed.

As many changes could be made in the above construction and many apparently widely different embodiments of this invention could be made without departing from

the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention, which as a matter of language, might be said to fall therebetween.

Having thus described my invention, what I claim as new and desire to secure by Letters Patent, is:—

1. In a hair curling apparatus, a plurality of independent heating devices, means whereby said heating devices are adjustable relatively to each other, and means whereby said heating devices are collectively adjustable as an entity.

2. In a hair curling apparatus, a plurality of independent heating devices, a plurality of counterweighted cables one for supporting each of said heating devices, and a single adjustable support for said counterweighted cables whereby said heating devices are collectively adjustable as an entity.

3. In a hair curling apparatus, a standard, a plurality of independent heating devices, a support, means independently adjustably connecting said heating devices with said support, and means whereby said support is adjustable upon said standard so as to adjust said heating devices collectively as an entity.

4. In a hair curling apparatus, a plurality of independent heating devices, a support therefor, a plurality of cables depending from said support one for connecting each of said heating devices to said support, means whereby the said cables adjustably connect said heating devices with said support to independently adjust the elevation of said heating devices with respect to each other, means whereby said support is adjustable to adjust the elevation of said heating devices collectively as an entity, and means for independently laterally adjusting said heating devices.

5. In a hair curling apparatus, a plurality of independent heating devices, a support therefor, a plurality of cables depending from said support one for connecting each of said heating devices to said support, means whereby the said cables adjustably connect said heating devices with said support to independently adjust the elevation of said heating devices with respect to each other, means whereby said support is adjustable to adjust the elevation of said heating devices collectively as an entity, a bracket comprising means whereby said heating devices may be independently laterally adjusted relatively to each other, and

means whereby said bracket is adjustable with respect to said support.

6. A hair curling apparatus, comprising a standard, a support, a plurality of independent heating devices, a plurality of cables hanging from said support to the lower end of which said heating devices are connected respectively, said cables being counterweighted whereby said heating devices may be adjusted vertically with respect to each other, means whereby said support is vertically adjustably connected to said standard, and a bracket also vertically adjustably connected to said standard comprising means for engaging said cables whereby said heating devices may be adjusted laterally with respect to each other.

7. In a hair curling apparatus, a plurality of independent heating devices, and means whereby said heating devices are independently adjustable relatively to each other comprising a common support formed of a plurality of radially projecting arms, a plurality of slides one carried by each of said arms, and means connecting said heating devices severally with said slides.

8. In a hair curling device, a plurality of independent heating devices, a support having a plurality of arms formed thereon, means whereby said heating devices are adjustably connected to said arms respectively to be adjusted vertically with respect to each other, and means whereby said connecting means is adjustable upon said arms to adjust said heating devices laterally with respect to each other.

9. In a hair curling device, a plurality of independent heating devices, a support having a plurality of arms formed thereon, means whereby said heating devices are adjustably connected to said arms respectively to be adjusted vertically with respect to each other, means whereby said connecting means is adjustable upon said arms to adjust said heating devices laterally with respect to each other, and means whereby said support itself is adjustably mounted whereby said heating devices may be collectively adjusted as an entity.

10. In a hair curling device, a standard, a plurality of independent heating devices, means whereby said heating devices are independently laterally adjustable relatively to each other, and auxiliary means also for providing lateral adjustment of said heating devices relatively to each other.

11. In a hair curling device, a plurality of heating devices, a support, means for adjustably connecting said heating devices to said support whereby said heating devices are vertically adjustable with respect to each other, means comprised in said support whereby said heating devices are adjustable laterally with respect to each other, and auxiliary means whereby said heating de-

vices are rendered independently laterally adjustable with respect to each other.

12. In a hair curling device, a plurality of heating devices, a support, means for adjustably connecting said heating devices to said support whereby said heating devices are vertically adjustable with respect to each other, means comprised in said support whereby said heating devices are adjustable laterally with respect to each other, auxiliary means whereby said heating devices

are rendered independently laterally adjustable with respect to each other, and means whereby said heating devices are collectively adjustable as an entity.

In testimony whereof, I affix my signature in the presence of two witnesses.
